Primary Examiner — Cynthia Ramirez(74) *Attorney, Agent, or Firm* — Christopher J. Volkmann; Kelly, Holt & Christenson, PLLC(57) **CLAIM**

The ornamental design for a paint sprayer apparatus frame, as shown and described.

DESCRIPTION

FIG. 1 is a perspective view of a paint sprayer apparatus frame showing my new design;
 FIG. 2 is a front view thereof;
 FIG. 3 is a back view thereof;
 FIG. 4 is a right side view thereof;
 FIG. 5 is a left side view thereof;
 FIG. 6 is a top plan view thereof; and,
 FIG. 7 is a bottom plan view thereof.

The broken lines shown in the Figures are for the purpose of illustrating portions of the paint sprayer apparatus frame and form no part of the claimed design.
